UNITED STATES PATENT OFFICE.

MYRON ROUNDS, OF BOSTON, MASSACHUSETTS.

ARTICULATED CAR.

No. 884,420.

Specification of Letters Patent. Patented April 14, 1908.

Application filed January 18, 1907. Serial No. 352,916.

To all whom it may concern:

Be it known that I, MYRON ROUNDS, a citizen of the United States, residing in Boston, in the county of Suffolk and State 5 of Massachusetts, have invented an Improvement in Articulated Cars, of which the following description, in connection with the accompanying drawings, is a specification, like letters on the drawings representing like 10 parts.

This invention relates to a railway car especially designed and adapted for use on railways having curves of short radii, and more particularly on street railways.

15 The invention has for its object to provide an articulated car, composed of a plurality of members or sections, each of which may be of the length and capacity now commonly employed on street railways, and which are 20 enabled to be used on the tracks now laid and having curves of substantially short radii, without causing the ends of the car to project over the curved tracks to such distance, as would interfere with traffic on the 25 street or the running of cars on double tracks laid in close proximity to each other and having sharp turns at street corners. To this end, the adjacent ends of the members or sections of the articulated car are pivotally 30 supported on a common truck extended beneath the said members below the level of the floors thereof, while the opposite ends of said sections are supported on separate trucks. The center truck may and prefer- 35 ably will be constructed as will be described, so as not to interfere with the usual steps at the adjacent ends or platforms of the car sections or members. These and other features of this invention will be pointed out 40 in the claims at the end of this specification.

Figure 1 is a side elevation with parts broken away of an articulated car embodying this invention. Fig. 2, a plan view of the car shown in Fig. 1. Fig. 3, a detail in plan 45 of the center truck. Fig. 4, a partial side elevation and longitudinal section of the truck shown in Fig. 3, and Fig. 5, a detail to be referred to.

50 Referring to the drawings *a, b* represent the two members or sections of an articulated railway car embodying this invention. The members *a, b* may be the same or different types of cars, as for instance the member *a* may be a closed car and the member *b* may 55 be an open car. The first may be used for

passengers who do not smoke, and the second for smokers.

Each of the members *a, b*, may be of the standard or usual length now commonly employed on street railways.

60 In order that the members *a, b* may be used on street railways having curves of substantially short radii and especially on systems having double tracks provided with such curves, the adjacent ends of the members *a, b* are mounted on a common truck *c*, which may be designated the center truck, while the said members have their opposite ends mounted on the trucks *d, e*, which may be of any suitable construction, such as now 65 commonly used on electric railways. The center truck *c* is provided with two pivots for the adjacent ends of the members *a, b*, and said pivots may be of usual construction and consists as herein shown of two upper 70 bearing plates *j, k*, and two lower bearing plates *m, n*, (see Figs. 3 and 4).

75 The upper bearing plates *j, k* are secured respectively to the bodies of the cars or members *a, b* and in the present instance, said bearing plates are secured to wooden blocks *o* fastened between longitudinal stringers or I-beams *p* upon which the floor *q* and crown piece *r* are laid.

80 The lower bearing plates *m, n* are secured upon a cross bar 10, which is supported by side frames 12, 13 of the truck *c*, the said side frames being connected at their ends by cross bars 14. The side frames 12, 13 have 85 secured to them castings 15, having outwardly extended arms 16, provided with sockets 17, (see Fig. 4) open at their lower ends for the reception of springs 18, the lower ends of which rest upon washers 19 and the upper ends of which bear against the end 90 walls of said sockets. The washers 19 are mounted on and supported by bolts 20 extended up through the end walls of the sockets 17 and through bars 21 of iron or steel, from which said bolts are suspended. The 95 bars 21 are firmly secured by the U-shaped bolts 24 to the top of the boxes 25 for the journals of the axles 26, 27, the said U-bolts passing under the said journal boxes and being secured by the nuts 28. The axles 26, 100 27, are provided with the usual wheels 30, 31.

105 It will thus be seen, that the adjacent ends of the car members or sections *a, b*, are supported by the truck frame comprising the side and end bars 12, 13 and 14, and that 110

this frame is in turn yieldingly supported by the springs 18, which are sustained from the journal boxes 25 by the bolts 24, the truck frame being guided in its vertical movement 5 by ribs 33 on the arms 16 of the castings 15 movable in vertical grooves in the journal boxes. It will also be noticed, that the journal boxes for the car axles 26, 27, are located between the car wheels, that is between the 10 car tracks, not shown, and that nothing projects beyond the car wheels, consequently ample room is afforded for the turning of the truck *c* on curves of substantially small radii without interfering with the steps or running 15 board 35 at the sides of the car member. So also, by pivoting the adjacent ends of the car members or sections in close proximity to their ends, as herein represented, the adjacent ends of the said members do not over- 20 hang or project beyond the tracks when rounding a curve of substantially small radius, to any material extent, and therefore a car embodying this invention is capable of being used on street railways having double 25 tracks laid on substantially narrow streets and provided with curves of substantially short radii at the street corners. It will also be seen, that the adjacent ends of the members or sections *a*, *b*, are substantially close 30 together, which enables passengers to pass from one car to another if desired and also enables one motorman and one conductor to operate practically two cars, thereby effecting a material saving in this respect. 35 The side spaces between the adjacent ends of the car may be closed by an extensible vestibule 37 of any suitable construction. Auxiliary supports for the adjacent ends of the members or sections *a*, *b* may be provided, 40 and for this purpose the frame of the truck *c* is provided at each corner with an antifriction device, such as a gear or pinion 40, which engages a curved rack 41 attached to the underside of the car body, and in the present instance, said rack bars are represented 45 in Fig. 2 as secured to bars 42 extended longitudinally of the car body.

I have herein represented one construction of articulated car embodying this invention, 50 but I do not desire to limit my invention to the construction shown.

Claims.

1. In a car of the class described, in combination, a plurality of car body members or 55 sections, trucks to support the same at the remote ends of adjacent sections or members, and a single truck interposed between the end trucks and extended under the adjacent

ends of said members or sections below the floors thereof, and means to pivotally secure 60 the adjacent ends of said members or sections separately to said single truck, substantially as described.

2. In a car of the class described, in combination, a plurality of car body members or 65 sections provided with side steps at their adjacent ends, trucks to support the remote ends of said members, and a center truck interposed between the said end trucks and extended under the adjacent ends of said 70 members below the floors thereof, said center truck being provided with axles having journal bearings between the wheels thereon, side bars supporting said journal bearings and a cross bar secured to said side bars between said wheels and substantially in line with the adjacent ends of said body members, and means to pivotally secure said adjacent ends to said cross bar, substantially as described. 75

3. In a car of the class described, in combination, two car body members, trucks to support the remote ends thereof, and a center truck extended under both body members below the level of the floors thereof and 85 to which the adjacent ends of said members are separately pivoted, substantially as described.

4. In a car of the class described, in combination, two car body members, trucks to 90 support the remote ends thereof, and a center truck extended under both body members below the level of the floors and having separate pivots for the adjacent ends of said members, substantially as described. 95

5. In a car of the class described, in combination, two car body members provided with doors in their sides at opposite ends thereof, trucks to support the same at the remote ends of said car body members, a 100 single center truck interposed between the end trucks and extended under the adjacent ends of said members below the floors thereof, separate pivots on said center truck for the adjacent ends of said members, and bearings on said center truck at its opposite ends to form additional supports for the adjacent ends of said members, substantially as described. 105

In testimony whereof, I have signed my 110 name to this specification in the presence of two subscribing witnesses.

MYRON ROUNDS.
